UNITED STATES PATENT OFFICE.

SIDNEY C. GAUNT, OF CHICAGO, ILLINOIS, ASSIGNOR TO BARNHART BROTHERS & SPINDLER, OF CHICAGO, ILLINOIS, A CORPORATION OF ILLINOIS.

DESIGN FOR A FONT OF TYPE.

No. 38,223.

Specification for Design.

Patented Sept. 4, 1906.

Application filed June 28, 1905. Serial No. 267,453. Term of patent 7 years.

To all whom it may concern:

Be it known that I, SIDNEY C. GAUNT, a citizen of the United States, residing at Chicago, in the county of Cook and State of Illinois, have invented a new, original, and ornamental Design for a Font of Type, of which the following is a specification, reference being had to the accompanying drawing, forming part thereof.

The drawing is a view of the characters of a font of type, showing my new design.

I claim—

The ornamental design for a font of type, as shown.

SIDNEY C. GAUNT.
